RAYMOND WELLS, OF HOMER, NEW YORK, ASSIGNOR TO COB WELL CORPORATION, OF CLEVELAND, OHIO, A CORPORATION OF VIRGINIA.

METHOD OF AND APPARATUS FOR EXTRACTING OILS AND THE LIKE.

1,357,365.

Specification of Letters Patent.

Patented Nov. 2, 1920.

Application filed February 29, 1916. Serial No. 81,144.

To all whom it may concern:

Be it known that I, RAYMOND WELLS, a citizen of the United States, and a resident of Homer, county of Cortland, and State of New York, have invented a new and useful Improvement in Methods of and Apparatus for Extracting Oils and the like, of which the following is a specification, the principle of the invention being herein explained and the best mode in which I have contemplated applying that principle, so as to distinguish it from other inventions.

The general aspects of the present improved method, or process, of extracting oils and the like, are the same as those set forth in my co-pending application, filed March 11, 1915, Serial No. 13,718. The present method, together with the apparatus, which I have specially designed for use in connection therewith, as in the case of the method disclosed in the aforesaid application, is particularly adapted for the rendering, drying and disposal of materials in which the oils, greases, or the like, to be extracted, are found in conjunction with a smaller or larger amount of water. Such method of disposal, in other words, is particularly adapted for the treatment of municipal garbage, abbatoir and rendering-house offals and refuse, and raw materials of fish, vegetable and meat canneries. As indicated, however, the invention is not limited to the treatment of the particular materials named, but is equally adaptable for the extraction of the essential oils from seeds, beans and other oil bearing vegetable substances.

As in the process of the aforesaid application, so in the method exemplified in the operation of the present apparatus, I mix the material to be treated in a suitable chamber, with a suitable medium such as naphtha or carbon tetrachlorid, insoluble in water, but capable of dissolving the oil or other ingredients to be extracted; thereupon raise the temperature of the mass to a point where the combined vapor tensions of such solvent and water are equal to, or greater than the vapor pressure in such chamber, thereby simultaneously evaporating such water with such medium; and add more of such medium so as to maintain the body thereof in such chamber, substantially constant.

In this general process, as heretofore carried out, I have utilized for the chamber in

which the foregoing operations are carried on, a flat, shallow receptacle of circular outline, into which the material to be treated is deposited so as to form a layer, of greater or less depth, covering the bottom of such chamber. In order to successfully carry out the several steps of the method or process it has then been necessary to manipulate the material, this being preferably accomplished by agitation through the medium of rotating arms disposed in the chamber, and near its bottom, and requiring to be driven by external power. Aside from certain practical considerations, limiting the size of a chamber of this sort, I have found that where the mass of material being treated is large in amount, the power consumption is a considerable item and adds materially to the cost of carrying on the process.

The object of the present invention, accordingly, is to provide a modification of the foregoing method of treatment, and apparatus, suitable for use in connection therewith, whereby the size of the charge of material may be greatly increased without encountering practical difficulties in the construction of the chamber, and whereby, furthermore, the necessity for stirring or agitating the material while being treated, is entirely obviated. In other words, with my present improved method and apparatus it is not necessary to manipulate the material at all, during its treatment, and at the same time the essential elements of the apparatus are arranged in much more compact form, requiring less space, and consequently reducing the size of the plant needed to handle any given quantity of material. To the accomplishment of the foregoing and related ends, said invention, then, consists of the steps and means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Figure 1 is a side elevational view, more or less diagrammatic in character, and with parts broken away in order to disclose the interior construction of an apparatus arranged for carrying out my improved proc-

ess or method; and Fig. 2 is an end view of the reduction chamber, forming the essential part of such apparatus.

Referring, first of all, to such reduction chamber 1, I preferably make the same of general rectangular form, the size and proportions thereof being, of course, subject to modification, depending upon the quantity and character of the material being handled. This chamber will preferably be constructed of sheets of metal, suitably riveted or welded together so as to be effectively airtight, and is completely closed save for the connections hereinafter to be described, and save for certain openings provided for the introduction and removal of the material being treated.

As indicated in the portion of the chamber, from which a lateral wall has been shown as being broken away in Fig. 1, said chamber is divided into a plurality of horizontal sub-chambers or compartments 2, six as shown, by means of correspondingly disposed partitions 3. The number of such compartments may be, of course, varied, as well as their relative heights, although for the purpose in hand, the compartments will be preferably of the same height, as shown. The partitions 3 in question, as also the bottom 4, or floor of the chamber, forming the bottom of the lowermost compartment therein, are of hollow construction, that is, they consist of two plates spaced a suitable distance apart, so as to permit of the introduction of steam, or like heating medium into such partitions and bottom wall, in order to heat the contents of the corresponding compartments. It has not been deemed necessary to show in detail the connections for supplying steam to these hollow partitions, as they will resemble in general, the connections employed with any steam jacketed apparatus or radiator. At one end of the chamber 1 a series of openings 5 are provided, one in alignment with each of the compartments formed as aforesaid, with the exception of the lowermost thereof, suitable doors 6 or other closures being provided, whereby such openings may be sealed while the operation is in progress.

Upon opening the doors 6 just described, however, each of the compartments is rendered accessible for the introduction, or removal, of one or more trays, or baskets 7, which are preferably provided with rollers 8 to facilitate their handling, both inside and outside of the compartment. These rollers at the same time serve to support such trays, or baskets, some distance above the floor of the compartment, as clearly shown in the drawing. The trays 7 are open on top, and their bottoms and walls are constructed of reticulated material, such as wire netting, or the like, so as to permit any liquid that may be supplied to the corresponding com-

partment, after the door thereof has been closed, to freely permeate the material being treated, which is intended to be disposed in such trays or baskets. This material will be thus disposed in the form of a relatively shallow layer, not to exceed six inches, for example, where it consists of garbage or the like, the level thereof being indicated in the trays in the upper compartment 2 by the dotted line a—a.

Connected with such upper compartment is a supply pipe 8 leading from a storage tank 9, which is preferably divided into two compartments 10, 10 by a transverse partition 11, with appropriate valve-controlled discharge connections 12, 12 from each, a pump 13 being interposed in this supply line, at a suitable point, unless gravity may be relied upon to provide a proper flow. Located preferably at a higher level than this tank, is a condenser consisting of several coils of pipe 14 in a suitable coiling tank 15. The discharge end 16 of the condenser coil is connected with a gravity separator 17, which is adapted to overflow from its upper end through a pipe 18 into either of the aforesaid storage chambers 10, a siphon overflow pipe 19 being connected with the lower end of said separator, and discharging into a waste pipe 20.

The condenser coil 14 is connected by means of one pipe 21 with the lowermost compartment 2 in the reduction chamber 1, and by means of another pipe 22, having suitable branches constituting a manifold 23, with all of the remaining compartments of such reduction chamber. Suitable control valves will, of course, be interposed in the aforesaid lines of pipe, as indicated, or found necessary, to properly regulate the flow of vapor or liquid, as the case may be, from one part of the general apparatus to another.

Assuming the trays, or baskets 7 to be supplied with the material to be treated disposed in a layer in each thereof as previously described, such trays to be placed in the several compartments 2 designed for their reception, and the latter to be thereupon sealed by closing the doors 6, the first step in the operation of the apparatus will consist in admitting solvent liquid from one or the other of the storage tanks 10, through the supply pipe 8 to the uppermost compartment. From this compartment the liquid in question is led by means of a series of valve-controlled by-passes 25 to each successive lower compartment, until such liquid attains a level in each such compartment an inch or so above the layer of material disposed in the trays supported in such compartment. Thereupon, the valves in the aforesaid by-passes are closed, and steam being admitted to the several hollow partitions 3, a temperature is quickly reached

which will cause the combined vapor pressures of such solvent and the water contained in the material, to equal the pressure above the mass in the respective compartments, so that water and solvent will begin to pass over through the manifold 23 and pipe 22 to the condenser coil 15. From the condenser such water and solvent, restored to liquid form, pass to the separator

- 10 17, where they are separated, the water overflowing to waste, and the solvent back to its appropriate storage tank 10. As the liquid level in the several compartments of the reduction chamber falls, more of such 15 solvent is added from time to time, or preferably, continuously, so as to maintain the body thereof in each chamber, substantially constant. For this purpose, valve-controlled overflow connections 26 from each compartment to the one immediately below are provided, whereby the level in each such compartment may be maintained, substantially 20 as hereinbefore indicated.

Such of the solvent as is allowed to percolate through the mass of material in the successive compartments before the first series of by-pass connections is closed, as well as the solvent that finally overflows from the lowermost of said compartments 30 during the stage of the operation last referred to, collects in the lowermost compartment, as will be readily understood. This compartment having likewise a steam-heated bottom, or floor, serves as a still, the vaporized solvent passing off through the pipe to the same condenser, as do the vapors from the compartments above. The dissolved oil or grease, however, carried by the solvent into this lowermost compartment, or still, 35 remains behind, and gradually accumulates, and at the end of the operation is drawn off through a suitable discharge pipe 27 provided for the purpose, as need not be further explained.

- 40 45 Upon completion of the extraction process proper, the doors to the respective compartments are again opened, the trays removed and emptied of their contents; whereupon they are ready to receive a fresh charge, and 50 the operation may then be repeated, using the same body of solvent over as often as desired.

The simplicity and compactness of the apparatus required to carry out this improved 55 process of extraction should be obvious; and the advantages in the process itself, requiring no manipulation or stirring of the material while in process, should be equally manifest. At the same time I am enabled 60 to retain all of the advantages inherent in the general process or method of treatment, wherein the water present in the material being treated is boiled off while the mass is immersed in the solution, and the extrac-

tion proper thereupon immediately proceeded with.

Other modes of applying the principle of my invention may be employed instead of the one explained, change being made as regards the steps or mechanism herein disclosed, provided the means stated by any of the following claims or the equivalent of such stated means be employed.

I therefore particularly point out and distinctly claim as my invention:—

1. In a method of extracting oils and the like from a material also containing water, the steps which consist in supporting a body of such material in a suitable chamber so as to be exposed above and below; supplying to such chamber a medium insoluble in water but capable of dissolving the oil or other ingredient to be extracted, the amount of such medium being sufficient to immerse such body of material; raising the temperature of the mass to a point where the combined vapor tensions of such medium and water are equal to or greater than the vapor pressure in such chamber, thereby simultaneously evaporating such water with such medium; and adding more of such medium, so as to maintain the amount thereof in such chamber substantially constant.

2. In a method of extracting oils and the like from a material also containing water, the steps which consist in supporting a body of such material in a suitable chamber so as to be exposed above and below; supplying to such chamber a medium insoluble in water but capable of dissolving the oil or other ingredient to be extracted, the amount of such medium being sufficient to immerse such body of material; raising the temperature of the mass to a point where the combined vapor tensions of such medium and water are equal to or greater than the vapor pressure in such chamber, thereby simultaneously evaporating such water with such medium; adding more of such medium, so as to maintain the body thereof substantially constant; and then drawing off the body of such medium with dissolved content of oil, or the like, after the water has been substantially all evaporated.

3. In a method of extracting oils and the like from a material also containing water, the steps which consist in supporting a body of such material in a suitable chamber in the form of a layer spaced from the bottom and top of the chamber; supplying to such chamber a medium insoluble in water but capable of dissolving the oil or other ingredient to be extracted, the amount of such medium being sufficient to immerse such body of material; applying heat to such medium below such material until the temperature of the mass is raised to a point where the combined vapor tensions of such

medium and water are equal to or greater than the vapor pressure in such chamber, thereby simultaneously evaporating such water with such medium; and adding more of such medium, so as to maintain the amount thereof in such chamber substantially constant.

4. In a method of extracting oils and the like from a material also containing water, the steps which consist in supporting a body of such material in a suitable chamber in the form of a layer spaced from the bottom and top of the chamber; supplying to such chamber a medium insoluble in water but capable of dissolving the oil or other ingredient to be extracted; the amount of such medium being sufficient to immerse such body of material; applying heat to such medium below such material until the temperature of the mass is raised to a point where the combined vapor tensions of such medium and water are equal to or greater than the vapor pressure in such chamber, thereby simultaneously evaporating such water with such medium; adding more of such medium, so as to maintain the body thereof substantially constant; and then drawing off the body of such medium with dissolved content of oil, or the like, after the water has been substantially all evaporated.

5. In a method of extracting oils and the like from a material also containing water, the steps which consist in supporting a body of such material in each of a series of suitable chambers in the form of a layer spaced from the bottom and top of the chamber; supplying to such chambers a medium insoluble in water but capable of dissolving the oil or other ingredient to be extracted, the amount of such solvent supplied to each chamber being sufficient to immerse the body of material therein; applying heat to such medium in each such chamber below such body of material until the temperature of the mass is raised to a point where the combined vapor tensions of such solvent and water are equal to or greater than the vapor pressure in such chamber, thereby simultaneously evaporating such water with such medium; and adding more of such medium to the first chamber in the series and thence passing the excess on to the other chambers in succession, so as to maintain the amount thereof in each such chamber substantially constant.

6. In a method of extracting oils and the like from a material also containing water, the steps which consist in supporting a body of such material in each of a series of suitable chambers in the form of a layer spaced from the bottom and top of the chamber; supplying to such chambers a medium insoluble in water but capable of dissolving the oil or other ingredient to be extracted,

the amount of such solvent supplied to each chamber being sufficient to immerse the body of material therein; applying heat to such medium in each such chamber below such body of material until the temperature of the mass is raised to a point where the combined vapor tensions of such solvent and water are equal to or greater than the vapor pressure in such chamber, thereby simultaneously evaporating such water with such medium; adding more of such medium to the first chamber in the series and thence passing the excess on to the other chambers in succession, so as to maintain the amount thereof in each such chamber substantially constant; and then drawing off the body of such medium, with dissolved content of oil or the like, after the water has been substantially all evaporated, such medium being thus drawn off from the last chamber of the series after passing in succession through the preceding chambers.

7. In a method of extracting oils and the like from a material also containing water, the steps which consist in percolating a medium insoluble in water but capable of dissolving the oil or other ingredient to be extracted through such material while stationary in a suitable chamber; then supplying such medium in an amount sufficient to immerse such body of material; and raising the temperature of the mass to a point where the combined vapor tensions of such medium and water are equal to or greater than the vapor pressure in such chamber, thereby simultaneously evaporating such water with such medium.

8. In a method of extracting oils and the like from a material also containing water, the steps which consist in percolating a medium insoluble in water but capable of dissolving the oil or other ingredient to be extracted through such material while stationary in a suitable chamber; then supplying such medium in an amount sufficient to immerse such body of material; raising the temperature of the mass to a point where the combined vapor tensions of such medium and water are equal to or greater than the vapor pressure in such chamber, thereby simultaneously evaporating such water with such medium; and adding more of such medium so as to maintain the amount thereof in such chamber substantially constant.

9. In a method of extracting oils and the like from a material also containing water, the steps which consist in percolating a medium insoluble in water but capable of dissolving the oil or other ingredient to be extracted through such material while stationary in a suitable chamber; then supplying such medium in an amount sufficient to immerse such body of material; raising the temperature of the mass to a point where the combined vapor tensions of such medium

and water are equal to or greater than the vapor pressure in such chamber, thereby simultaneously evaporating such water with such medium; adding more of such medium 5 so as to maintain the amount thereof in such chamber substantially constant, and maintaining the temperature of the mass until all of the water has been evaporated.

10. In apparatus of the character described, the combination with a series of suitable chambers adapted to receive and contain the solvent medium, the bottoms of said chambers being hollow, and arranged to receive a heating medium; of movable trays 15 adapted to support in said chambers bodies of material to be treated in the form of thin layers spaced from the bottoms and tops of the said chambers.

11. In apparatus of the character described, the combination with a series of superposed chambers adapted to receive and contain the solvent medium; of means for supporting the material to be treated in said chambers, respectively, except the lower-

most; heating means associated with each of 25 said chambers, liquid connections between each chamber and the one below; and a condenser having independent connections with said chambers.

12. In apparatus of the character described, the combination with a series of superposed chambers adapted to receive and contain the solvent medium; of means for supporting the material to be treated in 30 said chambers, respectively, except the lowermost; heating means associated with each 35 of said chambers; liquid connections between each chamber and the one below; a condenser having independent connections with said chambers; and solvent-supply connections to the uppermost of said chambers. 40

Signed by me, this 23 day of February, 1916.

RAYMOND WELLS.
